UNITED STATES PATENT OFFICE.

SVEN STALBERG, OF NAHANT, MASSACHUSETTS, ASSIGNOR TO GENERAL ELECTRIC COMPANY, A CORPORATION OF NEW YORK.

ADJUSTABLE DEVICE.

Application filed October 31, 1923. Serial No. 672,630.

My invention relates to adjustable devices, and in particular to adjustable devices especially adapted for use in connection with light projectors. Among the objects of my invention are the following: To provide a simple and rugged adjustable device; to provide an adjustable device comprising a swivel made in two sections, one end of the swivel arranged to rotate on a bearing and also adapted to receive between the sections a centering element, about which the swivel is adapted to rotate, the other end of the swivel being provided with an opening between the two sections for receiving a pivotally supported member adapted to be adjusted about an axis transverse the axis of the swivel; and to provide means for drawing the two sections of the swivel together, first, to clamp the swivel to its bearing and, second, to clamp the adjustable element to the swivel.

The means for accomplishing the foregoing and other useful ends are hereinafter more fully set forth and claimed, reference being had to the accompanying sheet of drawings.

Referring more in detail to the drawings, Fig. 1 shows the projector in elevation and partly in section; Fig. 2 is a front view of the device with a part broken away to more clearly show the universal pivot or joint by means of which the device may be set in any desired position in either or both of two intersecting planes; Fig. 3 is a detail drawing showing the hinge of the door of the device, in top view; Fig. 4 is a detail drawing of the latch for the door; Fig. 5 is a view in perspective of an element of the clamping device of the projector.

Referring more in detail to the drawings, the projector is provided with a suitable base 2 between which base and the casing 3 there is located a universal joint having an arrangement controlled by a single thumb screw 4. Projecting upwardly through the central portion of the base, I provide a swivel pin member 5 which member is provided with a hole through which the bolt 4 passes said member 5 serving as a link for locking the swivel 7 to the base or bearing element 2. This bolt also passes through a lug 6 which is suitably secured to the casing 3. The pin 5 is provided with a cut or groove into which the lug projects. The rotation of the lug 6 about the bolt 4 within

the said groove enables the casing 3 and the projector contained therein to be adjusted in any suitable position, in a vertical plane, for example, assuming the projector to be standing on a horizontal plane. Furthermore, the universal joint comprises a swivel or clamping element formed in two sections or halves 7 and 8. This clamping element in its lower part forms a hollow tubelike structure, which fits over the upwardly projecting stub or centering element 9 which latter serves as a bearing for the clamp and into the lower portion of which the stub projects, as clearly shown in Fig. 2. It will also be seen that the bolt 4 also passes through the two similar elements 7 and 8 suitable holes being provided in each of said elements. It will be understood that the two elements 7 and 8 are sufficiently separated in the zone where they overlap the plug 9 to prevent the two elements from touching when the thumb screw is tightened, as indicated by the dotted lines 10. While the lower portions of the elements 7 and 8 encircle the plug 9, the upper portions do not encircle the lug 6, but merely project upwardly along the sides of the lug 6, so that when the thumb bolt 4 is tightened, the faces 11 and 12 of the elements 7 and 8, respectively, clamp against the faces 13 and 14, respectively, of the lug 6. This arrangement is quite clearly indicated in Fig. 1. With this construction, by tightening the thumb bolt 4, the elements 7 and 8 of the clamping member are drawn together so that they are tightened against the stub 9 of the lower side and against the lug 6 on the upper side. In other words, a single hand operated clamping element 4 serves to lock the projector against the horizontal adjustment and also against the vertical adjustment. It will be understood that the thumb bolt 4 is provided with threads and at the same time the element 8 of the clamp is provided with threads, both of which sets of threads engage. The bolt, however, passes through the element 7 freely. Consequently, the turning operation of the thumb bolt when the projector is to be locked, draws the two sections 7 and 8 toward each other.

As shown in the drawings, the lug 6 is suitably secured to the casing 3, as for example, with rivets. The door 15 is fastened to the casing 3 by means of a hinge 16. In connection with the door a suitable latch

17 is also provided for locking the door closed. Secured to the frame of the door is a front glass plate 18. This may be done in any suitable manner as for example, by 5 means of clips 19 and screws 20. The reflector element 21 which may be of glass or of any other suitable type, is secured to the casing along the rim 22 on the front part of the projector. This clamping is 10 accomplished through the medium of clips 23 and screws 24. As shown in the drawing, the screws pass through the casing and through the clips 23 and engage a nut on the front side of the clip 23. This arrangement of the screws may be reversed and the 15 head of the screw may be on the front side of the clip while the nut may be located behind the rim 22 where the head is now shown. The rear portion of the frame 3 20 is perforated and drawn out to receive a tubular holder 25 in which there is a suitable socket 26 for holding the lamp 27 which constitutes the source of light. With the arrangement shown after the socket 26 25 is in position, the lamp 27 is put in place through the door 15.

The socket 26 is secured to the tube 25 in any suitable manner as for example, it may have a threaded element which passes 30 through the left-hand head of the tube 25 and it is held in place by the nut 28. The lamp 27, together with the socket 26, may be adjusted with respect to the focal point by sliding the tube 25 to the left or to the 35 right. For tightening the tube 25 in place, I provide a collar 29 which may be tightened about the neck 30 of the casing 3 by the thumb bolt 31. The neck 30 of the casing may be slit in order that the clamping 40 operation may be performed more effectively.

It will thus be seen that I provide an adjustable device comprising a base 2 with a ring bearing and a swivel formed in two 45 longitudinal sections 7 and 8, which swivel is mounted to rotate as a unit on its end on said bearing. Also I provide a centering element 9 projecting into the end of the swivel between the sections 7 and 8. Also 50 I provide an adjustable element 6 mounted on the other end of the swivel by means of the bolt 4, which element projects between the sections 7 and 8 of the swivel. It will be seen that the swivel bearing and 55 centering element have a common vertical shaft and that the adjustable element 6 has

a shaft transverse the shaft of the swivel. Furthermore, the arrangement of the parts is such that a plane through the axis of the bolt 4 and perpendicular to the face 11 60 of the element 6 will intersect a plane at right angles to the axis of the bolt 4 located between the faces 13 and 14 of the element 6, in a line which may be considered as a radial axis of the element 6 extending 65 transverse the axis of the bolt 4. Furthermore, this radial axis, by rotating the element 6 about its axis through the bolt 4 will generate a plane parallel to, or coincident with, a plane through the swivel axis 70 parallel to the face 13 of the adjustable element.

It will be understood that I do not wish to limit myself to the construction shown and described inasmuch as modifications 75 will readily suggest themselves to those versed in the art without departing from the spirit of my invention.

What I claim as new and desire to secure by Letters Patent of the United States 80 is:—

1. In combination, a ring bearing and hollow swivel, said swivel formed in two longitudinal sections and mounted to rotate as a whole on its end on said bearing, and 85 a centering element projecting into one end of the swivel between said sections, an adjustable element mounted on the swivel at the other end thereof to rotate thereon, said element projecting between the sections of 90 the swivel.

2. In combination, a ring bearing and hollow swivel, said swivel formed in two longitudinal sections and mounted to rotate as a whole on its end on said bearing and 95 a centering element projecting into one end of the swivel between said sections, an adjustable element mounted on the swivel at the other end thereof to rotate thereon, said element projecting between the sections of 100 the swivel, said swivel and bearing having a common axis about which axis the swivel is mounted to rotate, the axis of rotation of said adjustable element being transverse 105 the axis of rotation of the swivel, said adjustable element having a radial axis transverse its axis of rotation and located in a plane perpendicular to the plane of the ring bearing.

In witness whereof I hereunto set my 110 hand this sixth day of October, 1923.

SVEN STALBERG
